EXHAUST VENTILATOR

Ernest Leonard Ford and Richard James Rew,
Darlington, EnglandApplication December 5, 1929, Serial No. 411,913
In Great Britain December 14, 1928

6 Claims. (Cl. 98—20)

This invention relates to automatic exhaust ventilators for the closed compartments or bodies of vehicles, and in particular to that form of ventilator described and claimed in United States Specification No. 1,582,592 issued to one of us, and it has for its object a construction which is highly efficient at all speeds at which the vehicle may be moving which has no moving or loose parts liable to get out of order or lost, and which has a presentable appearance.

The present invention relates more particularly to improvements in the construction of the exterior parts of the ventilator and the construction of the interior is substantially the same as that described and illustrated in the aforesaid prior patent.

The object of this invention is attained by the construction shown in the accompanying drawing in which:

Figures 1, 2 and 3 are views in side elevation, end elevation and plan respectively, and,

Figure 4 is a section on line x—x of Figure 3.

The hollow body 1 which forms the exhaust chamber is of lozenge shape and has both its sides 2 and its top 3 of convex form. In each of the sides 2 are two apertures 4 and 5 the apertures 4 being approximate to one end of the body and those 5 being approximate to the other end thereof. These apertures are approximately V-shaped with their apices towards the ends of the body. On each side of the body are two exterior plates forming deflectors 6 and 7 which are preferably inclined or curved so as to coincide or register with the edges of the apertures 4 and 5 nearest to the ends of the body. At the tops of the deflectors 6 and 7 are horizontally or approximately horizontally disposed plates 8 which extend towards the centre of the body and preferably taper towards said point. The plates 8 are provided with apertures 9 which operate to intensify the negative pressure at the apertures 4 or 5 by reason of the flow of air over said openings. In each of the main deflectors 6 and 7 is a slot 10 which is located approximately in the centre of said deflector. The inner edge of each slot lies in substantially parallel relation to the side wall of the body 2 to which the inner edge of the deflector is attached, and the outer edge of the slot lies in substantially parallel relation to the outer or side edge of the deflector. From the inner edge of the slot 10 in each deflector springs a diagonally arranged plate forming an auxiliary deflector 11 which extends outwardly towards the centre of the length of the apparatus.

The central part of the base is formed by two inclined plates 12 which slope upwardly towards one another so as to form by and between them a relatively narrow centrally arranged transverse aperture 13. The upper edges of the plates 12 which form the confines of the aperture 13 are preferably shaped to form upwardly curved lips 14. Located between the plates 12 and the top 3 are a series of vertically disposed plates 15, said plates being angularly arranged with respect to the longitudinal centre of the apparatus.

The action of the ventilator is as follows:

Assuming that the vehicle, to the body of which the apparatus is fitted, is in motion in the direction of the arrow—Figure 1—a flow of air will be set up over the body of the ventilator. If the speed of the vehicle is slow the air stream when it strikes the forward main deflectors 6 will in part pass through the slots 10 which increases the negative pressure at the forward side apertures 4 in the body of the ventilator, and in part flow outwards over the outer edges of said deflectors. The air stream then impinges on to the rear main deflectors 7 when the auxiliary deflectors 11 will assist in gathering the flow of the air stream into the apertures 5 of the body, thereby creating a positive pressure on the rear side of the central extraction aperture 13 within the body and thereby assist in the formation of a negative pressure at said aperture. As the air flow increases the streams passing through the slots 10 in the forward main deflectors 6 are, by the action of the auxiliary deflectors 11 thereon, thrown further out from the body of the ventilator, and such of them as meet the rear deflectors 7, escape through the slots 10 in said deflectors, thus eliminating any baffling action until such times as the speed of the air flow increases to an extent which causes the air flow through the slots 10 to flow further outwards until it meets the other air stream and passes over the edges of said main deflectors to merge with it and pass to the rear clear of the main deflectors 7 thus simultaneously setting up negative pressure at the side apertures 4 and 5 in the body 3.

What we claim is:

1. An exhaust ventilator comprising a chamber which consists of a base having a transversely arranged opening at the centre of its length, a top and a pair of converging side walls having openings located in opposed pairs near the ends of the chamber, plates forming exterior deflectors on the side walls of said chamber adjacent to said side openings, an aperture formed in each exterior deflector, an approximately horizontally disposed

apertured extension of the exterior deflectors, and a plurality of vertically and angularly disposed deflector plates located within said chamber on each side of the transverse aperture in the 5 base.

2. An exhaust ventilator comprising a chamber which consists of a base having a transversely arranged opening at the centre of its length, a top and a pair of converging side walls having openings located in opposed pairs near the ends of the 10 chamber, plates forming exterior deflectors on the side walls of said chamber adjacent to said side openings, an aperture formed in each exterior deflector, an approximately horizontally disposed 15 apertured extension of the exterior deflectors, an auxiliary deflector applied to each exterior deflector springing from the inner edge of said aperture and extending outwards towards the centre of the length of the ventilator, and a plurality of 20 vertically and angularly disposed deflector plates located within said chamber on each side of the transverse aperture in the base.

3. An exhaust ventilator comprising a chamber which consists of a base having a centrally 25 located transverse opening, a top and sides connecting said top and said base which converge towards each other and in which are angularly-shaped apertures which are located in opposed pairs near the ends of the chamber, inclined 30 plates on the side walls of said body forming exterior deflectors which register with the upper edges of said angularly-shaped apertures, an aperture formed in each exterior deflector, an auxiliary deflector applied to each exterior deflector 35 springing from the inner edge of said aperture and extending outwards towards the centre of the length of the ventilator, and a plurality of vertically and angularly disposed deflector plates located within said chamber on each 40 side of the transverse aperture in the base.

4. In combination in an exhaust ventilator comprising a lozenge-shaped chamber comprising a base which slopes upwardly towards the centre and has a centrally located transverse opening, a 45 top, and side walls extending between said base and said top and having angularly-shaped apertures which are located in opposed pairs near the ends of the chamber, inclined plates forming exterior deflectors on the side walls of said chamber which register with the edges of said apertures nearest to the ends of the chamber, an 50 aperture formed in each of said inclined plates, an approximately horizontally disposed apertured extension of the exterior deflectors, an auxiliary deflector applied to each exterior deflector springing from the inner edge of said aperture and ex-

tending outwards towards the centre of the length of the ventilator, and a plurality of vertically and angularly arranged plates located in proximity to the two edges of the central aperture in the base of the chamber which operate as 55 interior deflectors.

5. A double-ended symmetrical exhaust ventilator comprising a base sloping upwards towards the centre of its length and having a relatively narrow transversely arranged opening at 60 said centre, a top above said base, a pair of forwardly converging side walls and a pair of rearwardly converging side walls between said base and said top and having angular openings, the edges of which nearest to the ends of the ventilator slope upwards and backwards from the base to the top, a pair of forwardly and a pair of rearwardly inclined plates on the exterior of the side walls which register with the sloping edges of the 65 openings in said side walls, an aperture formed in each of the forwardly and rearwardly inclined plates, an auxiliary plate springing from the inner edge of the aperture in each of said inclined plates and disposed approximately parallel with the converging side walls, and a plurality of deflector plates in the interior of the ventilator on each side of the central opening in the base and extending vertically from the base to the top.

6. A double-ended symmetrical exhaust ventilator comprising a base which slopes upwards towards the centre of its length and has a relatively narrow transversely arranged opening at 70 said centre, a top above said base, a pair of forwardly converging side walls and a pair of rearwardly converging side walls between said base and said top and having angular openings, the edges of which, nearest to the ends of the ventilator, slope upwards and backwards from the base to the top, a pair of forwardly and a pair of rearwardly inclined plates on the exterior of the side walls which register with the sloping edges of the 75 openings in said side walls, horizontally disposed apertured extensions of said inclined plates at their upper ends, an aperture formed in each of the forwardly and rearwardly inclined plates, an auxiliary plate springing from the inner edge of the aperture in each of said inclined plates and disposed approximately parallel with the converging side walls, and a plurality of angularly 80 arranged vertical plates extending from the base to the top and located in proximity to the two edges of the central transverse aperture in the base of the chamber which operate as interior deflectors.
